HIGHWAY GUARD FOR WET TRAFFIC LINES

Robert Glenn Corbin, Huntingdon, Pa., assignor to Wald Industries, Inc., Huntingdon, Pa., a corporation of Pennsylvania

Application April 3, 1956, Serial No. 40,888

Term of patent 14 years

(Cl. D72—1)

Fig. 1 is a top plan view of a highway guard for wet traffic lines showing my new design;

Fig. 2 is an end view in elevation;

Figs. 3 to 7, inclusive, are views in perspective taken from various angles and with the guard in varying but natural positions that the guard may take upon the highway.

I claim:

The ornamental design for a highway guard for wet traffic lines, as shown.
